G. C. FAVRE

GRINDING MACHINE

Filed Oct. 12, 1925

UNITED STATES PATENT OFFICE.

GEORGE CHARLES FAVRE, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

GRINDING MACHINE.

Application filed October 12, 1925. Serial No. 62,033.

This invention relates to new and useful improvements in grinding machines and has more particular reference to a grinding machine employed for beveling the edges of 5 ophthalmic lenses.

The primary object of the present invention is to provide a grinding machine of the character stated provided with a new and novel mounting for grinding stones.

10 Another important object of the invention is to provide such a stone mounting whereby the grinding stone will be permitted to adapt itself to lenses of various curvatures.

Another object is to provide such a stone 15 mounting wherein the pressure created by the various surface shapes of lenses will tend to oscillate the stone to conform with the irregularity of the periphery of lens being ground.

20 Another object is to provide such a stone mounting having positive means in the mounting thereof whereby to create in response to the pressure of the lens due to its surface shape an oscillating movement to 25 compensate for the irregularity of the periphery of the lens.

A further object is to provide such a mounting of the character stated which is comparatively simple and inexpensive in its 30 construction yet strong and durable and well adapted for the purposes for which it is designed.

With these and other novel features, the 35 invention resides in the particular construction, combination and arrangement of parts to be more fully hereinafter described, illustrated in the accompanying drawing, and particularly pointed out in the appended claims.

40 In the drawings forming a part of this application and in which is disclosed a preferred embodiment of the present invention:

Figure 1 is a side elevation of a stone 45 mounting constructed in accordance with the present invention.

Fig. 2 is a diagrammatic plan view of a grinding machine showing the arrangement of the various elements.

Fig. 3 is a sectional view of the stone 50 mounting, showing the different positions assumed by the stone during the grinding of a lens.

Figure 4 is a fragmentary sectional view showing the relationship of the lens with the grinding stone.

In the drawings, wherein like characters of reference denote corresponding parts throughout the several views, there is disclosed a grinding machine including a shaft 10 mounted in the journals or bearings 11, 60 and driven by the belt and pulley 12 and 13.

65 Mounted on the drive shaft 10, and rotatable therewith is a hub designated as a whole by the numeral 14, and comprising a pair of collars 15 and 16 held together by a plurality of fastening bolts 17, and being fixed or secured on the shaft by a set screw or the like 18. The bolts 17 are positioned at equally spaced distances around said collars 15 and 16, the adjacent faces of which are partially 70 cut away or recessed to form an annular groove 19.

A grinding stone 20 encircling the said collars has the rings 21 and 22 positioned at opposite sides thereof, and adjacent its inner edge, these rings being clamped onto the stone by means of a plurality of bolts 23 arranged at equally spaced distances around the circumference of said rings and in staggered relation to the fastening bolts 17.

80 The grinding stone 20 is spaced from the collars and is supported by a plurality of flexible members 24 which radiate from the hub 14, the inner end of each of said members being pivotally secured to one of the fastening bolts 17, while the opposite or outer end thereof is likewise pivotally secured to the bolt 23 directly in advance of the bolt 17, to which the inner end is secured, the term "in advance of" meaning in the direction of rotation of the shaft 10.

85 Positioned forwardly of the shaft 10 is a pair of horizontally aligned clamping shafts 25 and 26, supported within the journals 27 and 28. Between these shafts is arranged to be clamped, the lens 29 to be received and ground within the V-shaped groove 30 of the grinding stone 20, said shafts 25 and 26 being driven by means of the belt and pulley 31 and 31' respectively.

90 Carried by the shaft 26 is a former 32, the size and shape of which are adapted to be imparted to the finished lens. This former is held in contact with the former shoe 33

through the medium of suitable spring means 34, which also serves to retain the lens within the groove of the grinding stone.

The principle and operation of the invention is as follows: when it is desired to bevel the edges of a lens, the said lens is first clamped between the shafts 25 and 26, and is held within the groove 30 of the grinding stone, after which the said lens, together with the stone, is caused to be rotated. As the lens and stone rotate, the pressure upon the stone will be varied according to the surface shape of the lens, with the result that the stone will be oscillated to conform to the curvature thereof.

As an example, let us assume that it is desired to bevel the edge of an elliptical lens having a curved surface, such as shown in Figure 4. When this lens is rotated and engages with the stone at the point A, it will have a difference in position longitudinally than when it engages the stone at the point B. The lens having the curved surface will have a displacement longitudinally between the point A and the point B when the distance from the center to the point B is different than the distance from the center to the point A. This is true of all curved surfaces including spherical and toric surfaces, that is, where the curved surface has the same curvature in the two major meridians or where it has a different curvature in the two major meridians. Of course, this displacement is only true for a spherical lens where the shape of the lens is other than round, but in the case of a toric lens it is true even for a round lens. As the lens is rotated in the groove 30 of the grindstone there is a pressure set up tending to displace the edge of the grindstone in a direction parallel with the axis thereof. This pressure will cause the resilient members 24 to belly or flex so that the grindstone annulus 20 is displaced in a direction parallel with the shaft of the grindstone which keeps the bevel of the lens centrally disposed with respect to the edge of the lens.

From the above it will be readily appreciated that there has been provided a structure which will accomplish all of the objects and perform all of the functions claimed. It is also to be understood that various modifications may be found desirable when producing this mounting commercially, and the right is hereby reserved to make any such changes as properly fall within the scope of the appended claims without departing from or exceeding the spirit of the invention.

What is claimed is:

1. A grindstone mounting comprising a hub, an annular ring grindstone and a plurality of flexible flat blade bar members each having one end connected to the hub and the

other end connected to the annular ring, the material of said flexible blade bar members being disposed so that they are flexible in a direction normal to the plane of the grindstone.

2. A grindstone mounting comprising a hub, an annular ring grindstone and a plurality of flexible members each having one end pivoted to the hub and the other end pivoted to the annular ring, the material of said flexible members being disposed so that they are flexible in a direction normal to the plane of the grindstone.

3. A grindstone mounting comprising a grindstone shaft, a hub on the grindstone shaft having an annular groove therearound, an annular ring grindstone having a grooved ring on the inside of the annulus and a plurality of flexible members each having one end secured in the groove in the hub and the other end secured in the groove on the inside of the annular grindstone, the material of said flexible members being disposed so that they are flexible in a direction normal to the plane of the grindstone.

4. A grindstone mounting comprising a grindstone shaft, a hub on the grindstone shaft having an annular groove therearound, an annular ring grindstone, an annular grooved member on the inside of the grindstone annulus and a plurality of flexible members, each having one end pivoted in the groove of the hub and the other end pivoted in the groove of the grooved member on the inside of the annular grindstone, the material of said flexible members being disposed so that they are flexible in a direction normal to the plane of the grindstone.

5. A grindstone mounting comprising a grindstone shaft, a hub on the grindstone shaft, an annular ring grindstone and a plurality of flexible blade bar members connected to the hub and to the annular ring grindstone that will bulge or flex in a direction normal to the plane of the grindstone when pressure is applied to the edge of the grindstone to displace the edge of the grindstone in a direction parallel to the axis of the grindstone shaft.

6. A grindstone mounting comprising a grindstone shaft, a hub on the grindstone shaft, an annular ring grindstone and a plurality of flexible blade bar members having pivotal connections to the hub and to the annular ring grindstone so that they will bulge or flex in a direction normal to the plane of the grindstone when pressure is applied on the edge of the grindstone whereby the edge of the grindstone will be displaced in a direction parallel with the axis of the grindstone shaft.

GEORGE CHARLES FAVRE.
